U.S. Appl. No. 15/939,692, filed Mar. 29, 2018. (Unpublished).

Primary Examiner — Mark A Goodwin(74) *Attorney, Agent, or Firm* — Saidman Design Law Group(57) **CLAIM**

The ornamental design for a cutting edge for a ground engaging machine implement, as shown and described.

DESCRIPTION

FIG. 1 is a perspective view of a cutting edge for a ground engaging machine implement showing our new design; FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The drawings include CAD lines that represent contour and not surface decoration.
